CLAIM

The ornamental design for an instrument panel for a flow detector, as shown.

DESCRIPTION

FIG. 1 is a perspective view of an instrument panel for a flow detector showing my new design;

FIG. 2 is a front elevational view thereof;

FIG. 3 is a left side elevational view thereof; and

FIG. 4 is a top plan view thereof, the bottom being substantially flat, plain and unornamented.

FIG. 1.**FIG. 2.****FIG. 3.**

FIG. 4.

UNITED STATES PATENT AND TRADEMARK OFFICE
CERTIFICATE OF CORRECTION

PATENT NO. : D274,608
DATED : July 10, 1984
INVENTOR(S) : Fred Reslock

It is certified that error appears in the above-identified patent and that said Letters Patent are hereby corrected as shown below:

In the Title:

"Instrument Panel for a Flow Detector" should read

-- Instrument Panel for a Flaw Detector --.

Signed and Sealed this

Eleventh Day of June 1985
